UNITED STATES PATENT OFFICE.

HERMANN GEHNREICH, OF BROOKLYN, NEW YORK.

COMBINATION WINDOW AND SCREEN.

1,190,885.

Specification of Letters Patent. Patented July 11, 1916.

Application filed July 9, 1915. Serial No. 38,886.

To all whom it may concern:

Be it known that I, HERMANN GEHNREICH, a citizen of the United States, residing at Brooklyn, county of Kings, and State of New York, have invented new and useful 5 Improvements in Combination Windows and Screens, of which the following is a specification:

This invention relates essentially to that 10 class of windows in which the sash swings relative to a frame, the main object being to design screening means for covering the gap between the sash and the frame when the sash is operated to its open position. The 15 screening devices are adapted to shut out insects, prevent any articles from blowing out of the gap and it does not interfere with the admission of air or light.

The screening means consists of an upper 20 and lower segmental screen, one of the screens being secured to the upper portion of the frame while the other screen is mounted on the sash and moves inwardly or outwardly with the oscillation of the 25 sash.

The invention is more fully described in the following specification and claims and illustrated in the accompanying drawing in which:

30 Figure 1 is a vertical section of a window embodying this invention. Fig. 2 is a similar section showing the window open. Fig. 3 is a horizontal section taken along the line $x-x$ of Fig. 1. Fig. 4 is a detail horizontal section taken along the line $y-y$ of the same. Fig. 5 is a vertical section of a modification.

In this drawing the letter α designates a frame or casing which is preferably constructed of sheet metal and provided with a 40 sill and a head. At the lower, upper and inner side portions of the frame is located a mullion or parting strip b formed bylapping or doubling the metal. A metal glazed sash including rails c and a sheet of glass d 45 carried by the rails is arranged in the frame. The sash is provided with a flange e which normally engage or serve to shut the sash against the mullion. The sash is swingingly mounted at g to pivots h projecting from each side of the frame.

The upper inner portion of the frame is equipped with a curved screen i of fine wire mesh supported on side members j and provided with a stop k at the end of the screen 55 to limit the swing of the sash. This segment

tal screen has a radius clearing the arc of oscillation of the sash, and it covers the upper opening or gap between the frame and the sash when the sash is swung to an angle or tilted. The screen member is removably attached to the frame α by means of screws m in engagement with the frame. This method of mounting the screen on the frame permits it to be removed when it is desired to clean the window or another screen can 65 be substituted when it becomes worn.

Another segmental screen n supported on side members o is fixed to the bottom and side rails of the inner portion of the sash. The curvature of this screen forms an arc 70 with the oscillation of the sash and covers the lower outer gap when the sash is open as indicated in Fig. 2. The screen n is attached to the side members o by screws p in engagement with lugs q formed on the 75 side members. The screen can thus be dismounted from the members o merely by removing the screws. When the screens are removed the sash can be swung to any position to facilitate cleaning of the same.

80 It will be seen that the stop k limits the throw of the sash relative to the frame, but the movement could be increased by extending the screen to include a longer arc. The sash as shown swings vertically about the 85 center of the frame so that when it is opened the lower end of the sash will swing outward while the upper end swings inward. In this device the fine screening will effectively cover the upper and lower openings, 90 preventing things from blowing out and at the same time keeping out mosquitos, flies, or other objectionable matter.

95 The device can be utilized in connection with a transom, car or dwelling window, and the sash can be made to swing in any manner without departing from the scope of the invention.

Modifications of the invention may be made for example, the pair of segmental 100 screens can be secured to the frame α as indicated in Fig. 5. The lower screen n in this construction is removably attached to the outer side of the frame with the same radius as the upper screen to give clearance 105 room for the oscillation of the sash.

I claim:

110 1. A combination window and screen comprising a frame, a sash swingingly mounted on the frame, and a pair of segmental screens

projecting from opposite portions of the window in an arc with the oscillation of the ends of the sash to cover the gaps when the sash is opened.

5 2. A combination window and screen comprising a frame, a sash swingingly mounted on the frame, and a pair of screens arranged in an arc with the swing of the sash for covering the gap when the sash is open, one being secured to the sash and the other to the frame.

10 3. A combination window and screen comprising a frame, a sash swingingly mounted on the frame, an upper and lower screen arranged in an arc with the oscillation of the ends of the sash to cover the gap when the sash is open, one being secured to the sash and the other to the frame.

15 4. A combination window and screen comprising a frame, a sash centrally pivoted to swing on the frame, an upper screen secured to the frame, and a lower screen carried by the sash, said screens being arranged in an arc with the oscillation of the ends of the sash to cover the gap when the sash is open.

20 5. A combination window and screen comprising a frame, a sash pivoted to swing vertically on the frame, an upper removable

screen mounted on the frame and a lower removable screen carried by the sash.

30

6. A combination window and screen comprising a frame, a sash centrally pivoted to swing on the frame, a segmental screen secured to the frame, and a segmental screen carried by the sash, said screens being arranged in an arc with the oscillation of the ends of the sash to cover the gap when the sash is open.

35

7. A combination window and screen comprising a frame, a sash centrally pivoted to swing vertically on the frame, an upper segmental screen secured to the frame, and having a stop located on the screen to limit the movement of the sash, and a lower segmental screen carried by the sash, said screens being arranged in an arc with the oscillation of the ends of the sash to cover the gap when the sash is open.

40

In testimony whereof I have hereunto set my hand in the presence of two subscribing witnesses.
